(57) **CLAIM**

The ornamental design for an accent table, as shown and described.

DESCRIPTION

FIG. 1 is a front perspective view of the accent table of the present invention showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken line showing of elements on the table illustrate portions of the article and form no part of the claimed design.
